CATTLE BUNK FEEDER FILLER
Stanley W. Knight, Brodhead, Wis.
Filed Apr. 24, 1958, Ser. No. 730,576
2 Claims. (Cl. 214—519)

This invention appertains to vehicles for hauling material from one point to another, and for conveniently delivering such material when the point of use is reached, and more particularly to a novel mobile cattle bunk feeder and silo filler.

In the hauling and delivering of cattle feed, much difficulty is encountered. The green feed becomes compressed while being hauled and when the point of delivery is reached and the feed is moved forward in the wagon box by the longitudinal conveyor, the feed is compressed to a greater extent. The silage packs hard and firm in the box. This requires the use of high speed beaters to break up the silage for delivery and in many instances, the conveyors, beaters etc. break down under the strain.

It is one of the primary objects of my invention to provide a novel means, i.e., an expansion chamber forming a part of the hauling vehicle for permitting the expansion of the feed and the decompression thereof as the same reaches the beaters and the transverse conveyor employed for moving the material out of the box to the bunk feeder or silo as the case may be, whereby the material can be conveniently handled without undue load or strain on the operating mechanism.

A further important object of my invention is the provision of a cattle bunk feeder filler embodying a running gear having an expansion chamber or body thereon at the forward end thereof, the running gear receiving and supporting a desired type of wagon box for abutting engagement with the expansion chamber or body, the chamber or body being of a greater width than the box to form the desired decompression area for the feed.

Another salient object of my invention is the provision of a bunk or silo filler embodying a running gear for connection with a pulling vehicle such as a tractor, the running gear having mounted thereon and forming a part thereof, an expansion chamber provided with a novel arrangement of beaters and transverse conveyors for conveniently removing the feed from a wagon box of a desired character associated with the running gear, the running gear and expansion chamber forming a complete unit of manufacture so that farmers, if they so desire, can associate with the running gear and the expansion chamber a desired type of wagon box that may be preferred by the farmers.

A still further object of the invention is the provision of a novel and simple arrangement of operating parts associated with the running gear and chamber whereby such parts can be conveniently operated from a power takeoff shaft leading from the tractor or pulling vehicle.

A still further important object of my invention is the provision of a device of the above character, which will be exceptionally strong and durable in use, one that will be simple and easy to manufacture and one which can be placed upon the market at a reasonable cost.

With these and other objects in view, the invention consists in the novel construction, arrangement and formation of parts, as will be hereinafter more specifically described and claimed, and illustrated in the accompanying drawings, in which drawings,

FIGURE 1 is a perspective view of the improved vehicle looking from the front showing the running gear, expansion chamber and parts of the operating mechanism;

2

FIGURE 2 is a similar perspective view, but looking from the rear of the vehicle;

FIGURE 3 is a perspective view looking from the front but from the opposite side from FIGURE 1, and showing a wagon box attached to the running gear and the expansion chamber, and

FIGURE 4 is a fragmentary longitudinal sectional view through the front of the vehicle with the box mounted thereon, the section being taken on the line 4—4 of FIGURE 5, looking in the direction of the arrows, and

FIGURE 5 is a fragmentary detail horizontal sectional view taken substantially on the lines 5—5 of FIGURES 3 and 4, looking in the direction of the arrows.

Referring to the drawings in detail, wherein similar reference characters designate corresponding parts throughout the several views, the letter V generally indicates the improved vehicle and the same embodies a running gear 10.

The running gear 10 can actually be of any desired type or character, and as illustrated the same includes front and rear bolsters 11 and 12 rotatably supporting front and rear ground wheels 13 and 14. Firmly and rigidly secured to the bolsters 11 and 12 are longitudinally extending frame beams 15 and these beams are in turn united by transversely extending cross-brace beams 16. The extreme forward end of the running gear carries the expansion chamber 17, which forms an important part of the present invention. Also, in accordance with the invention the running gear is provided in rear of the expansion chamber 17 with upright stakes 18 and horizontal seats 19, for a purpose, which will now appear.

Associated with the running gear 10 in rear of the expansion chamber 17 is the wagon box 20. The wagon box can take various forms and as illustrated the same is of the barge type and hence includes straight parallel side walls 21, reinforced in any desired manner. The box 21 is supported upon sub-longitudinally extending sills or beams 22 and these sills or beams form a part of the wagon box. The box extends at least the full length of the running gear and abuts the chamber 17, as will be later brought out. The box is of the type embodying a longitudinally extending conveyor 23 and the top flight of the conveyor travels over the bed 24 of the wagon box. This conveyor extends forward of the box and into the bottom of the chamber 17, as best shown in FIGURE 4, for a purpose which will now appear. The conveyor 23 travels over front sprocket wheels 25 secured to a transversely extending drive shaft 26 rotatably mounted in suitable bearings carried by the forward ends of the side walls 21 of the box. The forward end of one side wall 21 rotatably carries a transversely extending operating shaft 27 having a driving connection preferably through a worm and worm wheel with the shaft 26 (see FIGURE 4). The worm wheel is keyed or otherwise secured to the shaft 26. The shaft 27 is provided with a sprocket wheel 28 and the sprocket wheel can be clutched to the shaft 27 by a hand operated clutch mechanism 29. The shaft 27 is driven through sprocket 28 by means, which will be later set forth.

As best shown in FIGURE 2, the chamber 17 is provided with a cut out portion 30 into which the drive mechanism just described fits. The sub-sills or beams 22 of the wagon body fit snug on the horizontal seats 19 and the stakes 18 engage the sides of the sub-sills and the stakes and the sub-sills are rigidly secured together in any desired way, such as by the use of bolts.

The forward end of the running gear carries a suitable tongue 31 for connection with a tractor or other pulling vehicle, not shown. At this point, it is to be also noted that the lower end of the chamber 17 at its front portion is provided with a main drive shaft 32 to which is coupled a power takeoff shaft 33 leading from the tractor.

The chamber 17 extends transversely across the running gear and is firmly and rigidly united therewith and includes a front wall 34 and side walls 35 and 36. These walls can be united by a floor 37. The rear edges of the side walls 35 and 36 are provided with inturned flanges 36', and the lower ends of these flanges carry a transversely extending upright guard plate 38. This plate 38 in effect forms a partial rear wall for the chamber and the floor 37, as best shown in FIGURE 4, is also connected to this plate. As also best shown in FIGURE 4, the longitudinal conveyor 23 extends into the chamber and partially over a transverse conveyor 39 carried by the bottom of the chamber. The upper flight of the conveyor 39 travels over the floor 37.

The wall 35 is provided with an outlet opening 40 for the silage and the conveyor 39 receives the silage from the longitudinal conveyor 23 and moves the silage toward and through the opening 40. Where the vehicle is being used as a silo filler, the material empties directly out of the vehicle into a blower utilized for filling the silo. When the vehicle is being used for filling cattle feeder bunks, a chute (not shown) is attached to the chamber and the chute is in turn provided with a conveyor for conducting the material to the bunk. The chute conveyor can be driven from the mechanism carried by the chamber and the chute is raised and lowered and held at different angles by a hand winch (not shown). The transverse conveyor 39 travels over sprocket wheels 41 carried by an operating shaft 42 and this shaft is carried by the chamber immediately below the opening 40. The forward end of the shaft 42 has keyed, or otherwise secured thereto, a sprocket wheel 42' and this sprocket wheel is driven from a chain 43 which is in turn trained about a sprocket wheel 43' keyed or otherwise secured to the main drive shaft 32. This shaft also has keyed thereto a second sprocket wheel 32', for a purpose which will later appear.

Mounted in the chamber 17 above the transverse conveyor 39 and the longitudinal conveyor 23, are upper and lower beaters 44 and 45. These beaters are carried respectively by shafts 46 and 47. These shafts are rotatably mounted in bearings carried by the end walls 35 and 36. Each beater has firmly secured thereto radially extending teeth 48 for engaging and breaking up the silage. The lower beater shaft 47 is driven from a countershaft 49 rotatably mounted in bearings on the end wall 36 and this shaft is driven from a sprocket chain 50, which is trained about the sprocket wheel 32'. This chain 50 is trained about a sprocket wheel 51 keyed to the countershaft 49. The shaft 49 drives the lower beater 45 through a speed reducing mechanism 52' and the same includes a worm and worm wheel. This is the same mechanism employed for driving the longitudinal conveyor from the shaft 27. The shaft 49 extends rearwardly of the chamber 17 and has keyed or otherwise secured thereto a sprocket wheel 52. The sprocket chain 53 is trained about sprocket wheel 52 and about the sprocket wheel 28 carried by the shaft 27. The upper beater 44 is driven from the lower beater, as is best shown in FIGURE 3. Hence, the lower beater shaft 47 at its end opposite from the drive 52', has keyed thereto a sprocket wheel 54. The upper beater shaft 46, has keyed thereto a similar sprocket wheel 55 and these sprocket wheels 54 and 55 have trained thereabout a drive sprocket chain 56. All of the sprocket chains are provided with a slack takeup mechanism of any preferred character.

Now referring to the connection of the box 20 with the chamber 17, it can be seen that the forward end of the box can be provided with vertically extending angle irons or the like 57. These angle irons are firmly secured to the front edges of the side walls 21 of the box and the angle irons 57 are in turn securely bolted to the inturned

flanges 36' carried by the walls 35 and 36 of the chamber. Thus, the box not only is firmly united with the running gear, but with the chamber itself. By referring to FIGURES 3 and 5, it can be seen that the box is of considerably less width than the chamber and consequently the chamber extends a material distance beyond the sides of the box. This is one of the features of the invention as heretofore set forth.

Considering that the packed feed is being moved toward and into the chamber 17, it is obvious that as it reaches the chamber that the same is allowed to expand. Thus, the chamber functions as a decompression body and as the feed expands the same can be easily pulled apart by the upper and lower beaters. As the material is expanding the beaters have materially less work to do and consequently, the beaters can be run at a low rate of speed. In actual practice, the lower beater 45 travels twenty percent faster than the upper beater 44. The running of the beaters at a low speed permits the same to act effectively on the feed to break up the same, and hence, the feed can be easily carried by the transverse conveyor 39 out of the chamber.

Great stress is laid on the combination of the running gear and the expansion chamber with all of the operating mechanism carried directly by the chamber and the running gear. Thus, after the box 20 is associated with the running gear, it is merely necessary to place the sprocket chain 53 in its operative position around the sprocket wheels 28 and 52. When this is done, the vehicle is ready for use.

Various changes in details may be made without departing from the spirit or the scope of my invention, but what I claim as new is:

1. A self-unloading vehicle for use in connection with a wagon box having a power driven conveyor for moving material toward an open forward end of the box comprising a running gear, a transversely extending body on the forward end of the running gear into which the material from the box is dumped and means in said body located at the end of and below said conveyor for receiving material dumped therefrom and for conveying the dumped material to one end of the body and out of the body, said body having a substantially greater length than the width of the box and projecting a material distance beyond the opposite sides of the box and constituting an expansion chamber for the material.

2. A self-unloading vehicle for use in connection with a wagon box having a power driven conveyor for moving material toward an open forward end of the box comprising a running gear, a transversely extending body on the forward end of the running gear into which the material from the box is dumped, said body including a front wall and end walls, the rear end of the body being open to receive the box and the forward end of the power driven conveyor, one end wall of said body having an outlet opening adjacent to its lower end and means in said body located at the forward end of and below said power driven conveyor for receiving material from said conveyor and for conveying the dumped material to and out of said opening, said body having a substantially greater length than the width of the box and extending a material distance beyond the opposite sides of the box and constituting an expansion chamber for the material.
